Application March 28, 1955, Serial No. 497,310

Claims priority, application Germany April 6, 1954

9 Claims. (Cl. 57—102)

The present invention relates to spinning or twisting spindles and, more particularly, to coupling means for use in connection therewith.

Spinning and twisting spindles, particularly those which are driven by a driving shaft through a positive drive such as worm wheel drive, screw drive or spur gear drive, comprise a clutch by means of which the spindles may be driven or may be drivingly connected to or disconnected from the driving shaft. The heretofore known clutches used in connection with such spinning or twisting spindles act by positive connection and/or frictional connection, for instance, while taking advantage of the centrifugal force of more or less heavy clutch members. Therefore, clutches of this type are relatively sensitive to torque. When large cop weights have to be dealt with, the clutches must accordingly be dimensioned rather heavy and voluminous in order to assure a safe carrying along of the loaded spindle. Inasmuch as the space available for arranging the clutch and driving elements for each spindle of a spinning or twisting machine is limited and cannot be increased without considerable changes in the entire construction of the machine, it is an object of the present invention to provide a clutch for spinning or twisting spindles which will allow a reliable operation of the spindle, even when large cop weights and greatly varying speeds are concerned, without considerable changes in the spinning machine.

It is another object of this invention to provide a spinning or twisting spindle with clutch means which will make it possible to start operation of the spinning or twisting spindle without shock.

It is still another object of this invention to provide a spinning or twisting spindle with clutch means which requires relatively little space and which will automatically be braked when the spinning or twisting spindle is drivingly disconnected by means of the clutch pertaining thereto from the drive shaft for said spinning or twisting spindle.

These and other objects and advantages of the invention will appear more clearly from the following specification in connection with the accompanying drawings, in which:

Fig. 1 represents a longitudinal section through the drive of a positively driven spinning or twisting spindle provided with a clutch according to the invention, said clutch being in its disconnected position.

Fig. 2 is a section similar to that of Fig. 1 showing the clutch in thrown position.

Fig. 3 is a diagrammatic cross-sectional view illustrating the operating mechanism for the clutch of Figs. 1 and 2.

Fig. 4 represents a longitudinal section through another embodiment of the invention.

Fig. 5 represents a longitudinal section through still another embodiment of the invention.

2

General arrangement

According to the present invention, the driving part for the spindle is connected with the driven part thereof through a clutch which when thrown in first establishes frictional driving connection between said two parts and subsequently a positive driving connection between said parts. Such double acting clutch may be designed in various manner. Thus, for instance, such clutch may comprise a sleeve which is drivingly connected with the driving shaft while being displaceable in axial direction thereof. Said sleeve cooperates with a driven part which may either be an element of the drive itself or of the yarn carrier. The sleeve and the driven part are provided with frictional surfaces and with means adapted to act as positive coupling members. The said frictional surfaces and said last mentioned coupling members are arranged relative to each other in such a manner that when the clutch is thrown in, first frictional connection between the elements to be coupled together will be effected and subsequently positive driving connection will be established between said parts to be coupled to each other. When driving a plurality of spindles from a single driving shaft, the clutch aggregate is expediently so designed that it can be mounted as an entirety on the drive shaft by means of an adjustable end sleeve adapted to be fixedly connected to the drive shaft. To this end, for instance, the clutch sleeve may be mounted on a resiliently slotted sleeve adapted to be clamped to the drive shaft and provided with an abutment. The arrangement may be such that said clutch sleeve is axially movable toward a drive wheel rotatably mounted on the same sleeve. The clutch members are so designed that those surfaces thereof which first engage each other when the clutch is thrown in form frictional surfaces of such width that the yarn carrier is carried along by frictional connection. Said frictional surfaces of both clutch members are followed by positive clutch members, for instance, jaws which are adapted to engage each other with peripheral play. If desired, the arrangement may also be such that the driven part may be provided with frictional and positive drive connecting elements and is displaceable toward a similarly designed clutch member which is rotatably connected to the driving part but is not displaceable thereon.

The actuating member for the displaceable clutch part may also operatively be connected with spindle braking means which, when disconnecting the clutch, will exert a braking force upon the yarn carrier so as quickly to stop the same.

Structural arrangement

Referring now to the drawings in detail and Figs. 1 to 3 thereof in particular, the structure shown therein comprises a spindle rail 1 of a spinning or twisting machine in which the spindle drive shaft 2 common to all of the spindles on the same side of the machine is journaled. In conformity with the respective spacing of the spindles, drives for the drive of the individual spindles are arranged on the drive shaft 2. According to the embodiment shown in Figs. 1 to 3, said drives comprise helical wheels 3 arranged to mesh with the helical thread 5 at the lower end of the respective spindle 4 proper.

With this arrangement according to the invention, the drive wheel 3 is freely rotatably mounted on a sleeve 6 which serves as carrier for the entire clutch aggregate so that the latter can be mounted as an entirety upon the drive shaft 2. To this end the sleeve 6 is provided with slots 7 which allow a certain spring. One end of the sleeve 6 is provided with a flange 8 which

serves as abutment at one end of the sleeve, whereas the abutment at the other end of the sleeve is formed by an adjusting ring 9 by means of which the sleeve 6 can be clamped fast to the driving shaft 2. This arrangement allows a precise adjustment of all driving wheels 3 on the drive shaft 2 with regard to the individual spindles 4 (one spindle only being shown).

The drive wheel 3 is fixedly connected to a bearing bushing 10 by means of a key 11 so that the wheel 3 cannot rotate on the bushing 10. On that side of the drive wheel 3 which is remote from the adjusting ring 9, there is arranged a clutch sleeve 12 which is non-rotatably connected to the sleeve 6 by means of a key 13, but which is axially displaceable so that the clutch sleeve 12 will be carried along by shaft 2 when the latter is rotated.

The clutch sleeve 12 is so designed and arranged that it is out of engagement with the drive wheel 3 when its outer surface abuts the flange 8 of the sleeve 6.

In order to bring about driving engagement between the clutch sleeve 12 and the drive wheel 3 in the manner intended by the present invention, the clutch sleeve 12 is according to the particular structure shown in the drawing designed hollow, whereas the drive wheel is provided with an extension extending in the direction toward said clutch sleeve 12. Said extension is adapted to enter a corresponding recess in the clutch sleeve 12 when the latter is moved against the drive wheel 3.

The extension of the drive wheel 3 is formed by rings 14, 15. The ring 14 represents a spacer ring, whereas the ring 15 has its circumferential surface provided with a friction liner or is a frictional slotted ring which by means of the key 11 similar to the wheel 3 is prevented from rotating about the bushing 10. The rings 14, 15 are prevented from moving in axial direction by a spring ring (Seeger-ring) 16. The frictional ring 15 is expediently designed similar to a Seeger-inner ring which by means of different cross-sections makes it possible when being compressed to allow uniform deformation and thereby uniform pressing pressures.

In the front portion of the recess 17 of the clutch sleeve 12 there is provided an annular frictional surface 18. That portion of said frictional surface 18 which is adjacent the front edge of the sleeve 12 has a smaller diameter than the subsequent portion of said annular frictional surface or frictional member 18. Said last mentioned portion of said frictional member 18 thus forms a kind of annular groove as is clearly visible from Figs. 1 and 2. When the clutch is thrown in, the frictional ring 15 can snap into said annular groove as is clearly shown in Fig. 2.

When the clutch is thrown in by moving the clutch sleeve 12 in the direction of the arrow *a* (Fig. 1), the parts 15 and 18 establish frictional driving connection. The positive driving connection is established by means of clutch teeth or clutch jaws 19 at the inner face of the sleeve 12 when said teeth or jaws 19 engage corresponding teeth or jaws 20 on the drive wheel 3. This will occur when the clutch sleeve 12 is moved in the direction of the arrow *a* until it abuts the drive wheel 3. The displacement or shifting of the clutch sleeve 12 is effected by means of a fork 22 engaging the groove 21 of the clutch sleeve 12. The fork 22 is adapted to be actuated by means of a tiltable lever 24 which is connected to the fork 22 by means of a pin 24a and an additional lever 23. The pin 24a is journaled in and guided by a sleeve 24b mounted in the spindle rail 1. The shiftable lever 24 may be provided with an extension 25 extending in the direction toward the respective spinning or twisting spindle 4. This extension 25 may be designed as a braking member for frictionally engaging the spindle 4 when the lever 24 is tilted for withdrawing the clutch sleeve 12 from coupling engagement with the drive wheel 3, i. e., when moving the clutch sleeve 12 in the direction of the arrow *b* (Fig. 2).

From the above, it will be evident that when throwing in the clutch sleeve 12, first the frictional surfaces or members 15 and 18 will frictionally engage each other, whereby the drive wheel 3 will be quickly but smoothly brought up to the speed of the drive shaft 2. While the clutch sleeve 12 is being moved further toward the drive shaft 3, the clutch teeth 19, 20 will engage each other without shock, particularly since they are arranged with peripheral play with regard to each other, whereby a positive engagement and drive of the spindle 4 to be driven is assured. After the clutch sleeve 12 has been completely thrown in, the friction ring 15 springs into the annular groove 18a of the frictional member 18 connected to the clutch sleeve 12, thereby preventing accidental disengagement of the clutch parts (Fig. 2).

If the spinning or twisting spindle is to be stopped, the clutch sleeve 12 is by means of the lever 24 shifted in the direction of the arrow *b* (Fig. 2) so that first the teeth 19 and 20 and only subsequently the frictional surfaces 15 and 18 disengage each other. Simultaneously with this operation, the spindle 4 is braked by the braking member 25.

Fig. 4 illustrates a spindle 4a which through the intervention of a whorl 26 and a belt is driven in force-locked manner. The whorl 26 is shrunk upon the spindle 4a so as to be fixedly connected thereto or may in any other way be non-rotatably and non-displaceably mounted on said spindle shaft 4a. Above the whorl there is a yarn carrier 27 or bobbin loosely placed upon the spindle shaft 4a in such a manner that it can rotate about shaft 4a, if desired, by means of anti-friction bearings (not shown in the drawing). This yarn carrier 27 is also adapted to be moved in the direction of the double arrow *c*. The term "yarn carrier" is to be understood generally to indicate any member or part of the spindle which receives the cop forming member such as a yarn sleeve or bobbin or the yarn itself.

The whorl 26 is provided with a hub extending in the direction toward the yarn carrier 27. This hub carries frictional power conveying means, namely, the friction ring 28, and also carries positive power conveying means, namely, the teeth or jaws 29 which are adapted to engage corresponding teeth or jaws 31 provided on the yarn carrier 27. The operation of the arrangement according to Fig. 4 is similar to that described in connection with Figs. 1 to 3. When the yarn carrier 27 is moved downwardly from the position shown in Fig. 4 by any convenient means, first the friction ring 28 frictionally engages the jaw-like elements 31 so that the yarn carrier is smoothly brought up to the speed of the driving whorl 26. When the yarn carrier 27 is moved further downwardly, the teeth or jaws 29 engage the teeth or jaws 31 so that the yarn carrier 27 is now positively carried along by the whorl 26. The friction ring 28 then snaps into the recess 30 and thus serves as safety holding devices for the clutch. In order to stop the yarn carrier, the yarn carrier is lifted, preferably by the same device by which it was lowered, whereupon the coupling or clutch parts will be disengaged from each other in a manner inverse to that described above.

If it is not desired or not permitted to move the yarn carrier in axial direction, and there is no space in the drive for a clutch aggregate, the arrangement may be modified as shown in Fig. 5. In this instance, the spindle shaft 4b either driven positively by a screw wheel drive 2a, 3a, 5a, or in a force-locked manner by a whorl 26a (indicated in dash lines), is provided with a splined section 32 on which a sleeve 33 is axially displaceable in the direction of the double arrow *d*. Above said sleeve 33 there is arranged the yarn carrier 27' which is rotatable about the spindle shaft 4b but is not axially movable thereon. The sleeve 33 and yarn carrier 27' are provided with frictional and positive engaging elements 28' and 29', 31' respectively, which represent the coupling members designed and operating in a manner

similar to those described in connection with Figs. 1 to 4. These clutch elements 28', 29', 31' will, depending on the axial movement of the sleeve 33 in one or the other direction, cause the yarn carrier 27' to be driven by the drive shaft 2a or to be stopped.

It is, of course, understood that the present invention is not limited to the particular constructions shown in the drawings, but also comprises any modifications within the scope of the appended claims. Thus, instead of the clutch members described and illustrated, also any other type of suitable clutch members may be employed. For instance, conical clutch members, disc clutch members, or centrifugal friction clutches may take the place of the friction rings described above. It is merely essential that first a synchronizing of the speeds of the driving and driven parts is effected by frictional connection before the positive driving connection is effected by means of which it is assured that the driven part is driven by the driving part at the speed of the latter.

I claim:

1. In combination in a textile machine: a spindle adapted to receive a yarn carrier, a drive shaft, first power conveying means arranged for driving connection with said drive shaft, second power conveying means carried by said spindle and arranged for driving connection with said first power conveying means, clutch members interposed between said drive shaft and said spindle for selectively establishing driving connection between said spindle and said drive shaft, said clutch members respectively comprising friction surface means arranged for frictional engagement with each other and also respectively including positive clutch means for positive coupling engagement with each other, said positive clutch means being arranged during a coupling process to become effective subsequent only to said friction surface means becoming effective, control means arranged for selectively bringing about movement of said clutch members toward each other or away from each other for respectively effecting or interrupting coupling engagement therebetween, and braking means associated with said spindle and operable in response to a relative movement of said clutch members away from each other to exert a braking force on said spindle to thereby stop the same.

2. In combination in a textile machine: a spindle, a yarn carrier supported by said spindle, a drive shaft, power conveying means interposed between said drive shaft and said spindle for conveying driving power to the latter, and coupling members respectively carried by said spindle and said yarn carrier and movable selectively relative toward each other or away from each other for respectively effecting or interrupting a coupling engagement between said coupling members, said coupling members respectively comprising friction surface means arranged for frictional engagement with each other and also respectively comprising positive clutch means for positive coupling engagement with each other, said positive clutch means being arranged during the creation of said coupling engagement to become effective subsequent only to said friction surface means becoming effective.

3. In combination in a textile machine: a spindle, a yarn carrier supported by said spindle, means for preventing axial movement of said yarn carrier on said spindle, a drive shaft, power conveying means interposed between said drive shaft and said spindle for conveying driving power to the latter, a first clutch member carried by said yarn carrier and comprising first frictional surface means and first positive coupling means, a second clutch member rotatably connected to said spindle but movable thereon in the axial direction of said spindle, said second clutch member comprising second frictional surface means and second positive coupling means, said second clutch member being movable toward said yarn carrier to bring about first coupling engagement of said first and second frictional surface means and subsequently

to bring about coupling engagement between said first and second positive coupling means.

4. In combination in a textile machine: a spindle for supporting a yarn carrier, a drive shaft, power conveying means for drivingly interconnecting said drive shaft and said spindle for conveying driving power to said spindle, said power conveying means including a gear substantially coaxial with and normally freely rotatable about said drive shaft, an annular clutch member surrounding said drive shaft and rotatably connected thereto, said clutch member being axially displaceable relative to said drive shaft and that end face of said clutch member which is adjacent to said gear being provided with coupling teeth, said gear being provided with complementary coupling teeth for engagement with the coupling teeth of said clutch member, a first friction member rotatably connected to the inner surface of said annular clutch member, said friction member having a substantially cylindrical inner friction surface coaxial with said drive shaft, a second friction member connected to said gear and having a cylindrical outer friction surface for frictional engagement with the inner friction surface of said annular clutch member, said second friction member and said first friction member normally being offset to each other in axial direction of said drive shaft, the coupling teeth of said clutch member normally being spaced from the complementary coupling teeth of said gear by a distance considerably greater than the normal spacing in axial direction between said first and second friction members whereby said friction members must frictionally engage each other prior to the engagement of said coupling teeth of said clutch member with the complementary coupling teeth of said gear.

5. In combination in a spindle driving mechanism for spinning and twisting machines: a shaft-like rotatable driving member, a driven member arranged coaxially with said driving member for selective driving connection therewith, a first clutch element rotatably connected to said driving member and axially displaceable thereon, said first clutch element being provided with coupling jaws, a second clutch element supported by said driven member and provided with recesses complementary to said coupling jaws for selectively receiving the same to effect a positive coupling between said driving member and said driven member, one of said clutch elements being provided with an annular frictional coupling member having a cylindrical outer frictional surface, and the other one of said clutch elements being provided with an inner cylindrical frictional surface for frictional engagement by said annular frictional coupling member, said clutch jaws and complementary clutch recesses and said frictional coupling element and cooperating frictional surface being offset with regard to each other in the axial direction of said driving member so that said frictional coupling member and the cylindrical cooperating frictional surface are normally spaced from each other by a distance considerably less than the distance between said clutch jaws and the cooperating clutch recesses to thereby positively cause frictional engagement between said frictional coupling element and the cooperating frictional cylindrical surface prior to the engagement of said coupling recesses by said coupling jaws when said first clutch element is being moved toward said second clutch element.

6. In combination in a spindle driving mechanism for spinning and twisting machines: a spindle for supporting a yarn carrier, said spindle being provided with a driving thread, a drive shaft, a gear coaxial with said drive shaft and meshing with said driving thread, said gear being equipped with a positively engageable first clutch element and normally being freely rotatable about said drive shaft, an annular frictional coupling member connected to said gear and having an outer cylindrical friction surface, a second clutch element rotatably connected to said drive shaft and displaceable in the axial direction thereof, said second clutch element being equipped with means for

positively engaging said first clutch element and also being equipped with a cylindrical frictional inner surface for frictional engagement with said outer cylindrical frictional surface, the distance between said frictional coupling member and said frictional inner surface in axial direction of said drive shaft normally being considerably less than the distance between said first and second clutch elements in axial direction of said drive shaft whereby said clutch elements can be positively engaged with each other only after preceding frictional engagement of said frictional inner surface with said frictional outer surface, control lever means for displacing said second clutch element selectively toward or away from said first clutch element, and brake means connected to said lever means for braking said spindle when said second clutch element is being withdrawn from said first clutch element.

7. An arrangement according to claim 4, in which said first friction member has sections of slightly different inner diameter for causing the section with smallest inner diameter to snap behind said second friction member when the coupling teeth of said annular clutch member positively engage said complementary coupling teeth.

8. An arrangement according to claim 5, which includes a sleeve rotatably connected to said driving member and carrying as an entirety said driven member, said second clutch element, and said frictional coupling member.

9. In combination in a spindle driving mechanism for spinning and twisting machines: a rotatable driving member, a driven member arranged coaxially with said driving member for selective driving connection therewith, a first clutch element rotatably connected to said driving member and provided with coupling jaws, a second clutch element supported by said driven member and provided with recesses corresponding to said coupling jaws for selec-

tively receiving the same to effect a positive coupling between said driving member and said driven member, said clutch elements being selectively movable relative toward or away from each other for respectively effecting or interrupting coupling engagement of said clutch elements, one of said clutch elements being provided with an annular frictional coupling member having a cylindrical outer frictional surface and the other one of said clutch elements being provided with an inner cylindrical frictional surface for frictional engagement by said annular frictional coupling member, said clutch jaws and cooperating clutch recesses and said frictional coupling member and cooperating frictional surface being offset with regard to each other in axial direction of said driving member so that said frictional coupling member and the cylindrical cooperating frictional surface are normally spaced from each other by a distance considerably less than the distance between said clutch jaws and the cooperating clutch recesses to thereby positively cause frictional engagement between said frictional coupling member and the cooperating frictional cylindrical surface prior to the engagement of said coupling recesses by said coupling jaws when said clutch elements are being moved relative toward each other.
